CLAIM

The ornamental design for a display screen or portion thereof with graphical user interface, as shown and described.

DESCRIPTION

FIG. 1 is a front view of a display screen or portion thereof with graphical user interface showing the new design.

FIG. 2 is a figure index of partial view FIGS. 2A and 2B showing the orientation of FIG. 2A with respect to FIG. 2B. FIG. 2A is a first partial front view of the display screen or portion thereof with graphical user interface of FIG. 1 displayed on and within the environmental structure of the display screen or portion thereof, as oriented in the figure index of FIG. 2; and,

FIG. 2B is a second partial front view of the display screen or portion thereof with graphical user interface of FIG. 1 displayed on and within the environmental structure of the display screen or portion thereof, as oriented in the figure index of FIG. 2.

All broken lines represent environmental subject matter, structure, and/or features that form no part of the claimed design. Specifically, the dash broken lines form portions the design that form no part of the claimed design, whereas the dot-dash lines depict the limits or boundary of the claim and likewise form no part of the claimed design.
